SYRINGE AMPOULE

Arthur E. Smith, Los Angeles, Calif.

Application May 22, 1939, Serial No. 275,055

1 Claim. (Cl. 128—272)

This invention relates to syringe ampoules.

The general object of the invention is to provide an improved ampoule construction for use in a syringe.

A more specific object of the invention is to provide a novel cork for use in an ampoule.

A further object of the invention is to provide a novel one piece cork including a piston portion and a chamber for holding a drug.

Another object of the invention is to provide a cork having a chamber therein and having an integral hinged trap door closure for the chamber.

Other objects and the advantages of this invention will be apparent from the following description taken in connection with the accompanying drawing, wherein:

Fig. 1 is a central sectional view through an ampoule showing the features of my invention;

Fig. 2 is a section taken on line 2—2, Fig. 1;

Fig. 3 is a fragmentary side elevation of the ampoule shown in Fig. 1;

Fig. 4 is a fragmentary sectional view on an enlarged scale showing the trap door opened;

Fig. 5 is a view similar to Fig. 4 showing the piston cork moved to the front end of the ampoule;

Fig. 6 is a view similar to Fig. 1 showing a modification;

Fig. 7 is a fragmentary side elevation of the ampoule shown in Fig. 6;

Fig. 8 is a fragmentary sectional view on an enlarged scale showing the trap door opened; and

Fig. 9 is a view similar to Fig. 8 showing the trap door opened and the piston moved to its forward position.

Referring to the drawing by reference characters I have shown my invention as embodied in an ampoule which is indicated generally at 10. The ampoule is preferably a cylindrical glass tube having end faces which are arranged at right angles to the axis of the tube. In the ampoule I show a front cork 11 which as shown includes a body portion 12 having an inwardly extending skirt thereon forming a chamber 14.

The chamber 14 communicates with the reduced chamber 15 which is closed by a diaphragm 16. The diaphragm 16 is spaced from the outer end of the cork 11 and forms the inner wall of a small chamber 17.

At the rear end the ampoule includes a cork 18 comprising a rubber body having an end recess 19 which is closed by a thin diaphragm 20. The body includes a chamber 21 and an

integral flap closure, or trap door, 22 which is integrally united to the body of the cork at one side as at 22' thus forming a hinge while the remainder of the trap door, as shown, is spaced from the edge 23 of the cork body. The periphery of the trap door 22 and of the body of the cork is cylindrical and both fit within the ampoule with the body of the cork slidably and forming a piston.

10 In Figs. 4 and 5 my improved device is shown as employed in a syringe barrel 23 which has a front needle 24 thereon adapted to pierce the diaphragm 16 and thus establish communication through the needle with the interior of the ampoule. The barrel also includes a plunger 25 having a head 26 thereon which slides within the ampoule and forces the cork 18 forward. The head 26 includes a projecting portion 27 which fits in the recess 19 and includes a rod 29 which pierces the diaphragm 20 and advances with the plunger and shifts the trap door to the position shown in Figs. 4 and 5.

In Fig. 4 the plunger rod 29 has just dislodged the trap door 22 while in Fig. 5 the plunger is 25 advanced and has moved the outer cork 18 forward thus forcing the contents from the ampoule.

My invention is particularly adapted for the preparation of fresh solutions and in doing this the ampoule includes preferably a liquid vehicle 30 29 disposed in the ampoule and a medicinal preparation 30 which is disposed in the chamber 21. When the trap door 22 is moved the liquid 29 is allowed to mingle with the medicinal preparation 30 thus forming a fresh solution.

35 In Figs. 6 to 9, inclusive, I show a modification of my invention which is indicated generally at 40. In the modification the ampoule 41 includes a rear cork 42 having a recess 43 therein for the reception of the end of a plunger. The cork 40 42 also includes a lower recess 44 with a diaphragm 45 between the recess 43 and 44.

At its front end the ampoule includes a cork 46 having an end flange 46' and having a recess 47 with a diaphragm 48 closing the inner end of 45 the recess. The cork 46 further includes an inwardly extending tongue 49 integral with the front portion of the cork and integral with the tongue 49 I show a trap door 50 which is cylindrical and which fits the interior of the ampoule 50 to produce a tight seal. The trap door 50 is spaced from the front portion of the cork to provide a chamber 51 in which a medicinal preparation 52 is arranged.

The ampoule shown in Figs. 6 to 9, inclusive, 55 is adapted to be used in a syringe which includes

a barrel 53 having a plunger 54 movable therein whereby the rear cork 42 may be moved forward. The barrel also includes a front member 55 from which a hollow tube 56 extends. This hollow tube communicates with a needle 57 through which injection is made.

The tube 56 has an open end 58 and lateral openings 59 and the tube is of such length that when the ampoule is pushed forward against the front member the tube strikes and shifts the trap door 50 thus allowing the medicinal preparation 52 to mingle with the fluid vehicle 60 in the ampoule thus enabling a fresh solution to be prepared for injection.

From the foregoing description it will be apparent that I have invented a novel ampoule and cork construction which is simple in construction and highly efficient for its intended purpose.

Having thus described my invention, I claim:
In an ampoule for use in a hypodermic syringe, a cylindrical glass body having a stopper at one end thereof, a second stopper in the body 5 at the other end thereof, said second stopper including a body portion having a recess therein at the outer end thereof, a diaphragm forming the inner wall of said recess, said body having a chamber therein, said diaphragm forming the outer wall of said chamber and a trap door 10 integral with the wall of said chamber, said trap door being cylindrical and having its periphery sealingly engaging the interior of said ampoule and a medicinal preparation in said chamber.

ARTHUR E. SMITH.
